(57) **CLAIM**

We claim the ornamental design for a non-pneumatic tire, as shown and described.

DESCRIPTION

FIG. 1 is a top-front-left isometric view of a first embodiment of a non-pneumatic tire showing our design.

FIG. 2 is a bottom-rear-right isometric view of the non-pneumatic tire of FIG. 1.

FIG. 3 is a top plan view of the non-pneumatic tire of FIG. 1.

FIG. 4 is a bottom plan view of the non-pneumatic tire of FIG. 1.

FIG. 5 is a front elevational view of the non-pneumatic tire of FIG. 1.

FIG. 6 is cross-sectional view of the non-pneumatic tire of FIG. 1, taken at section line 6-6 of FIG. 5.

FIG. 7 is a rear elevational view of the non-pneumatic tire of FIG. 1.

FIG. 8 is a top-front-left isometric view of a second embodiment of a non-pneumatic tire showing our design.

FIG. 9 is a bottom-rear-right isometric view of the non-pneumatic tire of FIG. 7.

FIG. 10 is a top plan view of the non-pneumatic tire of FIG. 7.

FIG. 11 is a bottom plan view of the non-pneumatic tire of FIG. 7.

FIG. 12 is a front elevational view of the non-pneumatic tire of FIG. 7.

FIG. 13 is cross-sectional view of the non-pneumatic tire of FIG. 7, taken at section line 13-13 of FIG. 12; and,

FIG. 14 is a rear elevational view of the non-pneumatic tire of FIG. 7.

Broken lines in the drawings are used to show tire tread, a wheel rim, and segments of the non-pneumatic tire in the cross-sectional views shown in FIG. 6 and FIG. 13, and form no part of the claimed design.
